WINDOW CONSTRUCTION

John A. Loetscher, Dubuque, Iowa, assignor to
 Farley & Loetscher Manufacturing Company,
 Dubuque, Iowa, a corporation of Iowa

Application July 31, 1943, Serial No. 496,851

2 Claims. (Cl. 20—42)

This invention relates to a window construction.

Among the objects of the present invention are to provide a simple, economical window construction which, if desired, may be made in knock-down form, and which when installed permits of a number of adjustments of the window with respect to the frame so that the window may be placed in a completely closed position with respect to the frame, or may occupy an inwardly slanting position to provide an opening between the top of the window sash and the frame for ventilation purposes, or alternatively may be raised in such inclined position to provide an opening both at the bottom and at the top of the window sash, or alternatively may be raised even higher in such last mentioned position to provide a relatively large opening at the bottom of the window between the bottom of the window and the bottom of the window sill, or alternatively may be positioned substantially horizontally at the top of the window frame so that the window frame is completely open but with the sash juxtaposed and horizontally resting against the upper frame member, or finally so that the sash may be completely removed from the frame in this last mentioned position, thereby providing practically any type of ventilation for the window opening and practically any type of position for the window itself whereby to exclude the rain and close the opening completely in one position, to a series of adjustable positions providing rain exclusion and a number of adjustably sized ventilating openings at the window; to provide these and other objects of invention as will be apparent from a perusal of the following specification when taken in connection with the accompanying drawings, wherein:

Figure 1 is an exterior view of the window sash, showing the latter in completely closed position.

Figure 2 shows the window sash rearwardly inclined to provide and ventilate the opening at the top of the window sash.

Figure 3 is a rear view of the position of the sash shown in Figure 2.

Figure 4 is a view showing the inclined sash slightly raised or raised to its second adjustable notch to provide a fair sized ventilating opening at the bottom of the window sash, as well as at the top.

Figure 5 shows the window sash completely raised to horizontal position so that the entire cross sectional area of the window is open.

Figure 6 shows a rearward view of Figure 1, with the window in fully closed position.

Figure 7 is a view taken on line 7—7 of Figure 1.

Figure 8 is a view taken on line 8—8 of Figure 4.

Figure 9 is a view taken on line 9—9 of Figure 7.

Referring to the drawings, the invention is shown in connection with a window frame installation for a house 2 wherein there is provided the window frame facing members 4 mounted between the studs 3 and having the downwardly slanting bottom sill 6 resting upon the usual frame member 8 of the house. The sill is provided with the first step 10 and the second step 12. Extending rearwardly of the sill at the two sides are two substantially triangular or wedge-shaped side members 14 and 16 abutting the vertical facing members 4 and fastened thereto by nails 15. The top edges 18 and 20 of these side members 14 and 16 are provided with notches 22 and 24 for the reception of a rear horizontal cross support 26, secured to the side members 14 by nails 33. The rear inclined edges 28 and 30 of the wedge-shaped members 14 and 16 are provided along their marginal edges from the sill 6 upwardly a short distance, with guide strips 32 and 34 which at the bottoms, as at 36, are spaced from the step 12 of the sill. These guide strips 32 and 34, in connection with the cross bar 26, provide abutment means and a resting shell for the inclined position of the sash hereinafter referred to, all as shown in Figure 7.

The two vertical side window frame members 4 are provided with spaced notches 38 and 40, which notches are spaced vertically of the frame members to provide recesses for toes or projections 42 on the bottom rail 44 of the window sash. The upper horizontal facing member 4 abuts and extends below the house frame member 5, which overlies the horizontal stud or cross member 1.

The window sash comprises the bottom rail 44, the two vertical side rails 46 and 48 and the top rail 50. In addition there may be the cross rails 52 and 54 for the glass window panes 56. An adjustable catch 58 serves to hold the window sash vertically in closed position as shown in Figures 1 and 6. This catch may be swung or pivoted so as to release the sash for movement to the partially open position shown in Figures 2 and 3.

By reference to Figures 4 and 8 it will be seen that the toes or projections 42 of the bottom rail

of the window sash may be placed either in the notches 38 and 40. In these partially open positions the window sash will rest diagonally against the rear rail 26 to provide a ventilating opening below the bottom rail of the window sash, as well as an opening between the inclined window sash and the upper part of the window frame. Thus the window sash may be placed as shown in full lines in Figure 5 and in dotted lines in Figure 8, with the bottom rail 44 abutting the under surface 25 of the cross bar or jamb 29. In this position the projections 42 of the window will abut against the inner wall of the upper facing member 4 so that the complete and unobstructed ventilation of the open window frame is provided. It is also to be pointed out that in this position the window sash may be removed completely from the window frame for cleaning, or any other purpose.

In the position shown in dotted lines in Figure 7 the bottom rail 44 of the window sash rests upon the stepped portion 12 of the sill 6 and against the back rail 26. The window may be moved from that partially open position to the fully closed position shown in full lines in Figure 7 so that the bottom rail 40 will still lie in the stepped portion 12 of the window sill, but the upper edge of the window sash will lie against the facing members 4 and completely close the window opening.

Obviously the invention is not limited to the specific details of construction disclosed herein but is capable of other modifications and changes without departing from the spirit and scope of the appended claims.

Having thus described the invention, what is claimed as new and desired to be secured by Letters Patent is:

1. In combination, a window frame comprising a sill member, outer vertical facing members extending upwardly from the opposite ends of the sill member in a common plane, an outer horizontal facing member extending between said vertical facing members at the upper ends thereof, triangularly shaped side members extending upwardly from the sill member and inwardly from said facing members, each of said side members being spaced apart a greater distance than said vertical facing members, a first cross-bar extending between the outer edges of said side members in abutting relation to said horizontal facing member and spaced from the sill member a greater distance than said horizontal facing member, a second cross-bar extending between said side members and having its inner surface inclined to the plane of said facing members, a window sash received between said side members for free horizontal and vertical movement from a fully open position completely uncovering the opening formed by said sill member and said facing members to partially open positions and to a fully closed position abutting

said facing members and extending between said sill member and said first cross-bar, said second cross-bar being spaced vertically from said sill member to support the upper edge of the sash 5 when resting on the sill member in a first of said partially open positions inclined inwardly from the plane of said facing members, said second cross-bar being spaced horizontally from the first cross-bar to support the sash intermediately 10 when in fully open position abutting, at its lower edge, the under surface of said first cross-bar, and means to support the sash in a second of said partially open positions when raised from the sill member and resting on said second cross-bar.

2. In combination, a window frame comprising a sill member, outer vertical facing members extending upwardly from the opposite ends of the sill member in a common plane, an outer horizontal facing member extending between said vertical facing members at the upper ends thereof, triangularly shaped side members extending upwardly from the sill member and inwardly from said facing members, each of said side members being spaced apart a greater distance than said vertical facing members, a first cross-bar extending between the outer edges of said side members in abutting relation to said horizontal facing member and spaced from the sill member 25 a greater distance than said horizontal facing member, a second cross-bar extending between said side members and having its inner surface inclined to the plane of said facing members, a window sash received between said side members 30 for free horizontal and vertical movement from a fully open position completely uncovering the opening formed by said sill member and said facing members to partially open positions and to a fully closed position abutting said facing members and extending between said sill member and said first cross-bar, said second cross-bar being spaced vertically from said sill member to support the upper edge of the sash when resting on the sill member in a first of said partially open 35 positions inclined inwardly from the plane of said facing members, said second cross-bar being spaced horizontally from the first cross-bar to support the sash intermediately when in fully open position abutting, at its lower edge, the under surface of said first cross-bar, said sash having projections from its lower edge and said vertical facing members having notches in their inner edges to receive said projections and support the sash in a second of said partially open 50 positions when raised from the sill member and resting on said second cross-bar, and abutment means carried by said side member adjacent the sill member to prevent inward movement of the lower end of the sash when moved to said first 55 partially open position.

JOHN A. LOETSCHER.
